CHARLES HENRY BROWN AND PATRICK FRAZIER, OF BRECKENRIDGE, TEXAS

BLADE FOR ROAD SCRAPERS

Application filed March 6, 1931. Serial No. 520,664.

This invention relates to a blade structure for use in connection with terracing and grading machines as described and illustrated in Patent No. 1,774,469, dated Aug. 26, 1930.

5 A primary object of the invention is to so construct and mount the blade embodying this invention as to avoid the load being placed on the shank which holds the blade.

Another object is to so construct the cutter 10 blade support to provide for the throwing of the top of the mold board to handle wet earth and to position the cutting blade at a proper angle in regard to the soil. The blade is designed to be so set that the dirt assumes 15 a rolling motion and is thrown forward and towards the dump.

Another object is to so mount the blade as to provide for the change in the slant thereof with relation to the direction of motion and 20 also to operate as a brace for the ends of the blade.

In carrying out these objects, the invention is susceptible of a wide range of modification without departing from the spirit or sacrificing 25 any of the advantages of the claimed invention; there being shown in the drawing for illustrative purposes a preferred and practical form, in which:

Figure 1 represents a perspective view of 30 a grader equipped with this improved blade;

Fig. 2 is a perspective view taken from the front showing the blade and its mounting;

Fig. 3 is a transverse section taken through the blade and its support; and

35 Fig. 4 is a detail perspective view of a portion of its blade and its mounting taken from the rear.

In the embodiment illustrated the blade structure constituting this invention comprises a mold board 10 which supports the reversible cutting blade 20 which latter is bolted on the lower portion of the transversely curved mold board 10, the concave face of which extends forwardly and has its lower edge offset rearwardly to form a seat 11 to receive the cutter 20. The upper portion of the mold board 10 is of arc-shaped form and the cutter 20 has a different radius from the upper portion of the mold board so that the 50 top of the mold board may be thrown for-

wardly a proper distance to handle very wet earth and yet provide the proper cutting angle for the blade 20. This adjustment of the blade is accomplished through means of a segment 15 and its connection with a member 16 of a swivelled post 17. This swivelled post 17 is mounted in the upright socket member of a four-way casting or coupling 6 constituting a part of the grader frame. This post is suitably secured to the casting by any means a collar 18 resting on the upper end of the casting 6 and which has a pin 19 extending therethrough to hold the post in position.

The blade engaging portion of this post 17 shown at 16 is made flat and is pivotally connected at its lower end as shown at 16a to the segment 15 carried by the rear face of the mold board 10 which supports the cutting blade 20.

This blade or mold board carrying segment 15 is provided at its upper end with a plurality of transversely spaced apertures 21 to receive a bolt 22 which adjustably connects the mold board with the post.

The blade carrying mold board 10 which is swivelled by the post 17 and the center casting 6 may be of any suitable or desired length and is equipped with longitudinally spaced bearings 23 on its rear face in which is mounted the rod 24 on which the swivelled post is pivoted. This rod also forms a pintle for the segmental adjusting plate 25 for the swivelled mold board 10. This plate 25 is shown substantially semi-circular with 35 bearings 26 at its ends engaged with the pintle 24 adjacent the bearings 23 as is shown clearly in Fig. 1. This plate 25 is provided with a plurality of spaced apertures 27 extending vertically therethrough and which are designed to receive a locking pin 28 mounted to reciprocate vertically in a casting 7 depending from the frame member 5, said casting being provided with laterally and forwardly extending apertured arms to form supports for the pin. A coiled spring 29 surrounds the pin between two of the bearings and bears at one end against the upper bearing and at its lower end against another. 95

A suitable lever operable from the driver's seat is provided for manipulating the pin 28 and retracting it against the tension of the spring 29 to provide for the lateral adjustment of plate 25 which carries the mold board.

Mounted on the segmental plate 25 near the opposite ends thereof are two upstanding stops 30 here shown in the form of bolts 10 which are designed to engage the casting when the tongue or draft bar 8 is swung laterally in one direction or the other so that the swivelling of the mold board may be accomplished by this means without necessitating manual manipulation thereof. These stops 30 will hold the blade when the machine has been swivelled to a predetermined position so that all that is required of the driver is to release the locking pin 28 and 20 the blade will return to its place without further effort.

It is of course understood that these bolts 30 which form stops are adjustable and are previously set at the predetermined position 25 that the blade is desired to be swivelled and will save much time and annoyance to the operator when adjusting the cutting blade.

Owing to the transverse curvature of the mold board 10 with the top thereof setting 30 far forward in what might be termed overhung position this board will not load up and fall to the ground as does the ordinary grader blade, because when it gets as much dirt in front of it as it can handle, the cutting 35 edge of the blade 20 is raised from the ground. It simply has no tendency to overload. The mold board and blade rolls the earth and wet dirt over and over in front of the blade and the dirt falling each time 40 from its contact with the mold board actually ascribes a spiral whose pitch is as the angularity of and rise of the blade.

The machine is equipped with ground 45 wheels 40 and 41 which are preferably constructed as shown of sheet metal having sharp thin vertical edges to hold the machine on slanted banks and which operate when the dirt is soft enough to stick to roll it off of the wheel.

50 In use the draft means being hitched to the clevis or hitch member 45 and the blade carrying mold board 10 is swivelled until one end sets in front of the other generally at an angle of about fifty to sixty degrees. 55 The forward end of the blade as shown in Fig. 1 is lowered into the earth by throwing the lever which controls one of the ground wheels causing the wheel to swing forward and thereby occupy the position close to the 60 end of the blade so that the blade is supported and prevented from entering the ground too deeply. The other wheel and its controlling lever is pulled backward to cause its corresponding wheel to lower its end of the 65 mold board according to the desired posi-

tion. The mold board is then pitched forward and held in place in its desired position by means of the bolt 22 clamping through one of the apertures 21 in the segment 15. The blade being so set that the dirt is given a rolling motion and thrown forward and towards the dump. An important feature of the invention is the making of the upper part of the mold board 10 and the reversible cutter blade 20 of different radii which provides for the throwing of the top of the mold board to handle wet earth and position the cutting blade 20 at a proper angle in regard to the soil. 70

The adjustment of the depth of the cutter 80 on one side and height of delivery on the opposite side of the machine can readily be made by means of segment racks 31 and 32 and their levers 33 and 34 having the usual locking latches or dogs. 85

It will be obvious that the swivelling segment or plate 25 not only provides for change in the slant of the blade with relation to the direction of motion, but also operates as a brace for the ends of the blade. 90

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed. 95

We claim:

In a grading machine, a supporting structure, a cutting blade including a mold board arcuate in transverse cross section with its lower edge offset rearwardly to form a seat for a cutting blade, and a cutting blade also arcuate in transverse cross section and of smaller radius of curvature than the mold board disposed in said offset portion, the cutting blade being sheared off at an angle along its opposite edges to provide cutting edges of similar formation so that the blade may be reversed, the offset portion being of substantially the same width as the blade, the offset portion forming with the mold board an inclined shoulder to neatly receive the sheared off cutting edge of the blade. 100
